US0D1032283S

(12) United States Design Patent (10) Patent No.: US D1,032,283 S
(45) Date of Patent: * Jun. 25, 2024

(54) BAKEWARE ITEM

(71) Applicant: Zhejiang Shuaishuai Technologies Co., Ltd., Zhejiang (CN)

(72) Inventor: Dechu Huang, Zhejiang (CN)

() Term: 15 Years

(21) Appl. No.: 29/803,368

(22) Filed: Aug. 12, 2021

(30) Foreign Application Priority Data

Jun. 8, 2021 (CN) 202130353292.8

(51) LOC (14) Cl. 07-02

(52) U.S. Cl.

USPC D7/360

(58) Field of Classification Search

USPC ..... D7/323, 354, 355, 356-361, 409, 543, D7/545, 555, 584, 586, 402, 407; D9/425, 429-433, 455-456, 737, 756-762 CPC A21B 2/00; A21B 3/00; A21B 3/13; A21B 3/15; A21B 3/14; A21B 5/00; A21B 5/02; A23N 12/06; A23N 12/08; A23N 12/10; A47G 23/03; A47G 23/0633; A47J 36/022; A47J 36/025; A47J 36/027; A47J 36/2405; A47J 37/00; A47J 37/04; A47J 37/041; A47J 37/042; A47J 37/06; A47J 37/067; B65D 1/22; B65D 1/24; B65D 1/34; B65D 1/36; B65D 77/2008; B65D 81/343; B65D 85/36; B21D 51/10; F24C 15/10; F24C 15/12; F24C 15/14; F24C 15/16; F24C 15/164; F24C 15/18

(57) CLAIM

The ornamental design for a bakeware item, as shown and described.

DESCRIPTION

FIG. 1 is a front perspective view of a bakeware item design showing my new design.

FIG. 2 is a rear perspective view of a bakeware item.

FIG. 3 is a front view of a bakeware item.

FIG. 4 is a rear view of a bakeware item.

FIG. 5 is a left side view of a bakeware item.

FIG. 6 is a right side view of a bakeware item.

FIG. 7 is a top view of a bakeware item; and,

FIG. 8 is a bottom view of a bakeware item.

1 Claim, 8 Drawing Sheets
